UNITED STATES PATENT OFFICE

127,825

DESIGN FOR AN ADJUSTABLE LIGHTING FIXTURE

Ernest H. Greppin, Brighton, N. Y., assignor to
Wilmot Castle Company, Rochester, N. Y., a
corporation of New York

Application March 6, 1941, Serial No. 99,390

Term of patent 7 years

To all whom it may concern:

Be it known that I, Ernest H. Greppin, a citizen of the United States, residing at Brighton, in the county of Monroe and State of New York, have invented a new, original, and ornamental Design for an Adjustable Lighting Fixture, of which the following is a specification, reference being had to the accompanying drawing, forming part thereof.

Fig. 1 is a perspective view of an adjustable

lighting fixture, showing my new design, with the tilting head tilted in a direction toward the observer, and

Fig. 2 is a similar view with the tilting head tilted in a direction away from the observer.

I claim:

The ornamental design for an adjustable lighting fixture, substantially as shown.

ERNEST H. GREPPIN.
